UNITED STATES PATENT OFFICE.

FREDRICK J. BINDER, OF DETROIT, MICHIGAN.

DESIGN FOR A RING.

56,854.

Specification for Design.

Patented Jan. 4, 1921.

Application filed May 7, 1920. Serial No. 379,678. Term of patent 14 years.

To all whom it may concern:

Be it known that I, **FREDRICK J. BINDER**, a citizen of the United States, residing at Detroit, in the county of Wayne and State of Michigan, have invented a new, original, and ornamental Design for a Ring, of which the following is a specification, reference being had to the accompanying drawing, forming part thereof.

Figure 1 is a top plan view of a ring, showing my new design, and

Fig. 2 is a side elevation of the same.

I claim;

The ornamental design for a ring, as shown.

FREDRICK J. BINDER.
